UNITED STATES PATENT OFFICE.

RICHARD VARLEY, OF ENGLEWOOD, NEW JERSEY, ASSIGNOR TO THE AUTOcoil COMPANY,
A CORPORATION OF NEW JERSEY.

IGNITION SYSTEM FOR EXPLOSION-ENGINES.

No. 866,241.

Specification of Letters Patent.

Patented Sept. 17, 1907.

Application filed November 13, 1906. Serial No. 343,179.

To all whom it may concern:

Be it known that I, RICHARD VARLEY, a citizen of the United States, residing at Englewood, in the county of Bergen and State of New Jersey, have invented certain new and useful Improvements in Ignition Systems for Explosion-Engines, of which the following is a full, clear, and exact description.

My invention relates to ignition systems for explosion engines, and is particularly adapted for use in motor vehicles where a dynamo driven by the engine is used as the sole source of primary current, and batteries of every sort are dispensed with.

The use of batteries in motor vehicles is attended by much trouble and annoyance mainly on account of the fact that the amount of energy required for the engine ignition is large and beyond the capacity of any convenient portable battery, unless the same is renewed or recharged very frequently. Accordingly engine driven magneto generators are frequently used to supply the ignition current when the engine is running. Such generators answer all requirements except that they do not generate a current when the engine is at rest to enable the vehicle to be started from the seat. In carrying out my invention I provide a magneto generator which is arranged to be operated to generate a current while the engine is not in motion.

The invention consists in the features of construction and combination hereinafter set forth and claimed.

In the drawings: Figure 1 is a view of an auxiliary magneto generator included in an ignition system and embodying the principles of my invention; Fig. 2 is a detail view of a part of the same. Fig. 3 is detail view showing a slightly modified arrangement.

Engines with four or more cylinders are now almost universally used on all motor vehicles, except those of the light run-about class, and with an engine having this number of cylinders it is always theoretically possible to start the engine from a state of rest, since one of the four cylinders is bound to be within a quarter of a revolution of the normal ignition point, and the ignition timing devices are always capable of being manipulated enough to reach the ignition point for such one of the cylinders within these limits. Since this cylinder contains a carbureted mixture remaining from the intake when the engine was last running, it follows that such charge will be exploded and the engine started. This is not only theoretically the case, but is practically true for all cars which have finely built engines. The only requisite, therefore, is to obtain an ignition spark of sufficient intensity to ignite the charge which is often cold and only slightly compressed when the engine has been standing idle for a long time. The engine driven dynamo is of course not available when the engine is at rest.

In carrying out my invention I aim to provide a

source of current which is compact and convenient, and which has abundant energy to fire a poor mixture which has been left standing in the cylinders for a long time. I further aim to automatically cut out this auxiliary source from action when the engine has been started into operation.

Referring to the drawings in which like parts are designated by the same reference sign, 1 designates broadly a magneto generator which is formed to be attached upon the dashboard of a motor vehicle, and in a position convenient to be engaged by the foot of the chauffeur or his mechanician. This magneto generator is conveniently made with a box-shaped frame or casing 2, open at its front side, and having screw holes 3, by which any ordinary cover plate (not shown) may be secured thereto.

4 indicate the permanent magnets received upon pole pieces 5, attached to the casing 2, and 6 denotes the revoluble part or armature which is journaled in suitable bearings 7, on the pole pieces. This magneto 75 may be of the ordinary or any desired form, and the details of its construction constitute no part of my invention.

8 denotes a short shaft journaled in the casing 2, and having a large gear wheel 9 thereon, which is geared to 80 rotate the armature 6 by a multiplying gear train 10, 11, 12, the pinion 12 being on the armature shaft. Gears 10 and 11 are fixed on a shaft 13 journaled in the casing.

I provide means for rotating the shaft 8 through part of a revolution by the movement of the foot. For this 85 purpose a ratchet wheel 14 is fixed to the shaft 8, and a spring pressed pawl 15, carried by a lever 16, loose on shaft 8 is effective to turn the ratchet wheel 14 when the lever 16 is rocked. The lower end of the lever 16, is provided with a pedal 16'.

17 denotes a spring attached to the lever 16 and the casing 2, by which said lever is normally retracted. In its retracted position the lever rests against a fixed stop 18, which also constitutes an electrical contact, said stop being insulated from the casing 2 by an insulating block 19.

One of the armature terminals of the magneto generator 1 is grounded on the casing 2, while the other terminal has the ordinary spindle end connection with a plate 21. This plate 21 is in electrical connection by 100 a wire 22, with the stop or contact 18. This brush may also be connected in the ignition circuit in the manner shown diagrammatically at the lower part of Fig. 1.

The operation is as follows: The induction coils A', A², A³ and A⁴, are connected through any suitable circuit controlling devices B, C, with a dynamo or other suitable current source D, grounded at E. The magneto generator comprised by my invention is included in this circuit, the connection n' being grounded on the casing 2, while the connection n² runs to the plate 21. 110

I will suppose that the engine is at rest, and it is desired to obtain an ignition spark in one of the cylinders. The operator presses his foot on the pedal 16' of the lever 16, whereby said lever is swung inward, turning the ratchet wheel 14, and the shaft 8. The movement of the shaft 8 is multiplied through the multiplying gear train 9, 10, 11 and 12, so that the armature 6 of the auxiliary magneto generator spins around rapidly, making a large number of revolutions. Thus current passes through wire n^2 , and through one or another of the induction coils A', A², A³ and A⁴, according to the position of the circuit closer B. At the same time the usual timing lever on the steering wheel is manipulated to swing the circuit controlling devices backward and forward, so that the circuit of one or another of said induction coils is made and broken.

The circuit controlling devices may be of the usual form, or they may be of the character set forth in my companion applications, Serial No. 341,926, and No. 20 343,833, filed herewith, which construction is diagrammatically shown in Fig. 1. A plurality of spaced segments *h* are successively engaged by a grounded arm *i* and an arm *j* is impelled to break the primary circuit before its rupture at the successive segments. When the 25 engine is not running the primary circuit may be completed and broken by swinging the segments and arm *j* by the usual timing devices as above stated. This condition results in a spark produced by the secondary or induction coil, and this in turn starts the engine as 30 has been already described. In this action the dynamo D takes no part but the resistance of its armature is almost non-inductive and so slight as not to impair the efficiency of the ground connection E for the auxiliary magneto generator 1.

35 When the engine has been started the operator removes his foot from the pedal 16' which returns against the contact 18 by reason of its tension spring 17. In this position the lever makes a short circuit through the wire 22 between the circuit connections n' and n^2 , so 40 that the auxiliary magneto is wholly cut out of the ignition circuit. It, therefore, has no effect until it is again to be used.

The use of a mechanically driven generator for the 45 purposes of obtaining a starting current is not confined to an auxiliary generator, since the main generator may be connected to an auxiliary mechanism by which it is operated independently of the engine for starting purposes. In Fig. 3 I have shown a shaft 30, which is driven by the engine, and which may be utilized to 50 operate the magneto generator shown in Fig. 1 when the engine is running, the magneto then becoming the main generator for the engine. For this purpose the spindle 6 of the magneto is extended and provided with a clutch face 31, which has holes 32 therein. 33 indicates a collar splined to the shaft 30, and spring impelled toward 55 the disk 31 by a spring 34. 35 indicate pins which are spring impelled outward from the face of the collar 33. By this arrangement the collar 33 moves against the disk 31, and the pins 35 enter the holes 32, unless the collar 60 is constrained against such movement. 36 indicates a bell crank lever working in a groove 37 of the collar, so

that the latter may be moved into its non-engaged position when desired. With this form of the invention it is merely necessary to throw the bell crank to disengage the clutch in the above way, and then depress the 65 foot pedal 16' for the purposes of obtaining a starting current. As soon as the engine rotates, the bell crank 36 is released, and the clutch becomes automatically engaged by virtue of the spring 34 and the spring impelled pins 35.

What I claim, is:—

1. A means for starting explosion engines with an electrical ignition system, comprising an auxiliary generator having a foot pedal, and means whereby said generator is automatically cut into the ignition circuit when said pedal is depressed. 75

2. A means for starting explosion engines with the usual electrical ignition system and circuit controlling devices, comprising an auxiliary generator having a foot pedal, and non-electrical means for including said generator in the ignition circuit when said pedal is depressed 80 whereby the engine may be started by said circuit controlling devices.

3. A means for starting explosion engines with an electrical ignition system and circuit controlling devices, comprising an auxiliary magneto generator, a foot pedal, means for operating said generator when said pedal is depressed, and means for including said generator in the ignition circuit when said pedal is depressed. 85

4. A means for starting explosion engines with an electrical ignition system and circuit controlling devices therefor, comprising an auxiliary magneto generator in the ignition circuit, a foot pedal for operating said generator, and means for cutting said generator out of the ignition circuit when said foot pedal is in its undepressed position. 90

5. In combination with an explosion engine having an electrical ignition system, an auxiliary alternating current generator having one terminal grounded, and means whereby such generator may be included in the ignition circuit when desired in series with the usual current 100 source.

6. In an ignition system for explosion engines, a circuit controlling device having spaced segments, a plurality of induction coils having their primaries connected with said segments and to a common circuit, an auxiliary generator, and mechanical means for including said generator in said circuit when it is rotated. 105

7. In combination with an explosion engine having an electrical ignition system, an auxiliary magneto generator adapted to be positioned away from the engine and conveniently on the dash of a motor vehicle, said auxiliary generator having a foot pedal by which it is operated, and means operated by the depression of said foot pedal for cutting the generator into the circuit of the ignition system. 110

8. In an ignition system for explosion engines, a circuit controlling device having spaced segments, and a source of current, induction coils connected thereto, an auxiliary generator, and means for automatically cutting said generator into said circuit when it is operated. 115

9. In combination with an explosion engine having an electrical ignition system, an auxiliary alternating current magneto generator adapted to be located away from the engine and conveniently upon the dash of a motor vehicle, said generator having means adapted to be engaged and moved by the person operating the car, by which it is included in the ignition circuit and simultaneously caused to generate a current. 120

In witness whereof, I subscribe my signature, in the presence of two witnesses.
